UNITED STATES PATENT OFFICE.

ISADORE N. STRUMPH, OF NEW YORK, N. Y.

DETACHABLE CUFF FOR SHIRT-SLEEVES.

1,349,987.

Specification of Letters Patent. Patented Aug. 17, 1920.

Application filed July 29, 1919. Serial No. 313,972.

To all whom it may concern:

Be it known that I, ISADORE N. STRUMPH, a citizen of the United States of America, residing at New York city, county and State 5 of New York, have invented certain new and useful Improvements in Detachable Cuffs for Shirt-Sleeves, of which the following is a full, clear, and exact description.

This invention relates to improvements in 10 garment-sleeves, particularly shirt sleeves, the object being to provide a sleeve with a reversible cuff. To carry out my invention, I provide a sleeve with a detachable cuff arranged for reversal so that when one side 15 becomes soiled or frayed, the cuff can be turned over to present a clean or unfrayed side.

I will now proceed to describe my invention in detail, the novel features of which I 20 will point out in the appended claim, reference being had to the accompanying drawing, wherein:—

Figure 1 is a fragmentary perspective view of a sleeve made in accordance with 25 my improvement and also a cuff arranged for attachment thereto; and

Fig. 2 is an enlarged sectional view of a portion of the sleeve, the section being taken on a line 2—2 in Fig. 1.

In the drawing, Fig. 1, the numeral 5 indicates a portion of a sleeve, provided at its end with separable members 6 and 7 each provided with button-holes 8 and 9, respectively, to receive buttons 10 and 11 of a 30 cuff-member 12. The separable members 6 and 7 are provided by folding the material at the end of the sleeve in a special manner. To produce members 6 and 7, I turn the material of the sleeve inwardly as at 13, Fig. 2; 35 thence outwardly as at 14; then inwardly as at 15. In other words, the material of the sleeve at its ends is folded over to provide a relatively long inwardly projecting extension which is afterward folded outwardly 40 to form a second forwardly extending projection, which is finally folded intermediate its ends upon itself inwardly. These fold- 45 ed over portions are finally stitched together at 16, some distance from the end of the sleeve, thereby providing the separable flaps 50 or members 6 and 7 hereinbefore referred to. Each member or flap 6 and 7 is provided with the button-holes 8 and 9 hereinbefore referred to, to engage the buttons 10 and 11 on the cuff 12, said cuff being provided with 55 button-holes 17 and 18 to receive cuff-buttons. The inner end of the cuff 12 is inserted between the flaps or separable members 6 and 7 and secured by the buttons thereon, which are caused to engage the button-holes 8 and 9. 60

Should the cuff become soiled or worn out on one side it will be removed from engagement with the flaps 6 and 7 and reversed, that is to say the soiled side turned. In this 65 instance the buttons at corner A will engage the button-holes at the opposite corner B of the end of the sleeve 5. The double flaps between which the edge of the cuff is placed, will present a smooth neat appearing connection for a removable and reversible cuff. 70

What I claim as my invention is:—

A sleeve provided with a plurality of flap-members, said flap-members being formed by folding the material at the free 75 end of the sleeve upon itself first inwardly, then outwardly intermediate the ends of the inwardly folded portion of the sleeve, then inwardly intermediate the ends of the outwardly folded portion of the first named 80 inwardly folded portion, the folded over portions being secured together and to the sleeve at a point somewhat removed from the end of the sleeve to provide separable flap-members, a cuff arranged to be inserted 85 along a longitudinal edge thereof, between said flap-members and means to releasably secure the cuff and flap-members together.

Signed at New York city, N. Y., this 22nd day of July, 1919.

ISADORE N. STRUMPH.
